UNITED STATES PATENT OFFICE

GARRETT LAYTON GRIER, OF MILFORD, DELAWARE

DESIGN FOR A MIXING SLAB

Application filed February 21, 1933. Serial No. 47,282. Term of patent 14 years.

To all whom it may concern:

Be it known that I, GARRETT LAYTON GRIER, a citizen of the United States, residing at Milford, in the county of Sussex, State of Delaware, have invented a new, original, and ornamental Design for a Mixing Slab, of which the following is a specification, reference being had to the accompanying drawing, forming a part thereof, in which:—

Figure 1 is a plan view of a mixing slab showing my new design.

Figure 2 is a side elevation of the mixing slab shown in Figure 1, and

Figure 3 is a perspective view of the mixing slab shown in Figs. 1 and 2.

I claim:

The ornamental design for a mixing slab as shown.

GARRETT LAYTON GRIER.
